Watson E. Coleman, Attorney

UNITED STATES PATENT OFFICE.

RODERICK WEIR, OF MOBRIDGE, SOUTH DAKOTA.

SIPHON APPARATUS.

Application filed October 15, 1921. Serial No. 507,872.

To all whom it may concern:

Be it known that I, RODERICK WEIR, a citizen of the United States, residing at Mobridge, in the county of Walworth and State of South Dakota, have invented certain new and useful Improvements in Siphon Apparatus, of which the following is a specification, reference being had to the accompanying drawings.

10 This invention relates to water distribution devices, particularly to siphon apparatus, and has for its object the provision of a siphon apparatus adapted for use in connection with wells, ponds, lakes or other 15 bodies of water whereby to supply water to a reservoir such as a water-hole for watering stock or for any other purpose.

An important object is the provision of a 20 siphon apparatus having a pump associated therewith for starting the siphon action, use being made moreover of a specially constructed check valve at the inlet end of the siphon pipe.

A further and more specific object is the 25 provision of a siphon apparatus in which the discharge pipe of the pump is connected with the siphon pipe which has its inlet end carrying a gravity check valve provided with a constantly open relatively small hole, 30 the arrangement being such that when the pump is initially operated water passing therethrough will discharge all the air from the siphon pipe so as to facilitate starting the siphon action.

35 An additional object is the provision of an apparatus of this character which will be simple and inexpensive in construction and installation, highly efficient in use, positive in action, durable in service and a general improvement in the art.

With the above and other objects and advantages in view, the invention consists in the details of construction to be hereininafter more fully described and claimed, and 45 illustrated in the accompanying drawings, in which:

Figure 1 is a sectional view through a well illustrating my siphon apparatus in position; and

50 Figure 2 is a detail sectional view through the check valve.

Referring more particularly to the drawings, the letter A designates a well, at the top of which is mounted the usual platform

B upon which is secured a pump C of ordinary type which has an inlet pipe D extending down into the well in the usual manner and carrying the ordinary cylinder E. Instead of the usual spout the pump is provided with an outlet pipe 10 which connects 60 with a T 11, having one branch closed by a plug 11^a and having connected with its other branch a pipe 12 which leads down into the well and which has its lower end carrying a check valve 13 of peculiar construction as 65 will be hereinafter explained. Interposed in the pipe 12 is a suitable cut off valve 14 and a union 14^a of conventional pattern and connected with the pipe 12 at or near the platform B is a discharge pipe 15. 70

The check valve 13 comprises a casing 16 having an inlet end 17 within which is located a straining screen 18 held in place by a ring 19 screwed on to the casing. This casing is provided at its opposite end with 75 an internally threaded flange 20 into which is screwed the pipe 12. The casing may also be formed with a flanged extension 21 normally closed by a plug 22. Extending transversely of the casing 16 is a partition 23 80 formed with a central opening 24 which is normally closed by a flap valve 25 pivoted within the casing. The partition 23 is formed with a relatively small hole 26 which is always open. 85

Assuming that my device has been constructed and assembled as above described, the operation is as follows: When it is desired to start the siphoning action it is necessary to operate the pump C in the usual 90 manner, the valve 14 of course being open. Water passing from the pump will be forced through the pipe 12, some of the water passing into the pipe 15. As the water is forced down the pipe 12 it will force out all the 95 air from the pipe 12 through the hole 26 in the check valve casing so that in a very short time the pipe 12 will contain nothing but water. Owing to the fact that the water cannot escape through the hole 26 with 100 as great rapidity as it is pumped into the pipe 12, it will be apparent that the water will be forced through the pipe 15, the discharge end of which is below the level of the check valve 13 whereupon the siphoning action will start as soon as the valve 14 is closed and the pumping action discontinued. It is then apparent that the water will con- 105

tinue to flow through the pipe 15, being drawn through the screen 18 and through the opening 24 in the check valve, the flap valve 25 of course being unseated.

- 5 In order to provide against freezing of the water within the pump and pipes in case the apparatus is not in operation, I provide the pump C with a small pet cock 27 and the pipe D with a waste hole 28. It will be 10 obvious that when the pet cock is open the water within the pipe D and pump will drain back into the well when the pump is standing idle. The cut off valve 14 is provided with a hole 29 which permits draining 15 out of the water above the valve.

The purpose of employing the T 11 and plug 11^a in place of an L is that the plug may be removed and the well pumped dry in case it is necessary to clean it, or repair the curbing or renew the screen 18, all these being capable of accomplishment without interfering with the action of the siphon.

The purpose of the hole 26 is threefold: first, to effect priming of the siphon; second, 25 to drain water out of the pipe 12 when the siphon is stopped; and third, for cleaning the screen 18 whenever the siphon is started. As far as the priming action is concerned, the hole 26 would cause the same result regardless of its exact location in the check valve, though by forming the hole in the partition, the discharge of water through the hole will wash away any débris or rubbish which may have accumulated on the screen 30 18 during the previous siphoning.

From the foregoing description and a study of the drawings it will be apparent that I have thus provided an extremely simple apparatus by means of which water may

be siphoned from a well, pond, lake or other body of water where the use of a siphon is practicable, simple mechanism being provided for starting the siphoning action by means of an ordinary pump. The operation may be attended to even by a child as no great intelligence and very little strength are necessary. Owing to the simplicity of the construction it is apparent that there is nothing to get out of order and that the device should consequently have an extremely long life and efficiently perform all the functions for which it is intended.

While I have shown and described the preferred embodiment of the invention it is of course to be readily understood that I 55 reserve the right to make such changes in the form, construction and arrangement of parts as will not depart from the spirit of the invention or the scope of the sub-joined claim.

Having thus described my invention, I claim:

The combination with a siphon embodying the usual induction leg, said leg being provided upon the lower end thereof with a 65 screen, of means for forcing fluid into said leg in a direction opposite to the normal direction of flow therethrough, and a check valve disposed at the lower end of said leg opening in the direction of normal flow and 70 having an opening permitting passage of fluid at all times, said opening being smaller than the inlet for the oppositely directed fluid.

In testimony whereof I hereunto affix my 75 signature.

RODERICK WEIR.
